US0D1089866S

(12) **United States Design Patent** (10) Patent No.: **US D1,089,866 S**
(45) Date of Patent: ** Aug. 19, 2025

(54) **ACCESSORY FOR FIRE HELMET**

(71) Applicant: **MSA Production France SAS**,
Chatillon sur Chalaronne (FR)

(72) Inventors: **Frederic Dias**, Chatillon sur
Chalaronne (FR); **Victor Lejeune**, Yate
(GB); **Karl Jones**, Yate (GB)

(**) Term: **15 Years**

(21) Appl. No.: **35/522,002**

(22) Filed: **Jun. 25, 2024**

(80) **Hague Agreement Data**

Int. Filing Date: **Jun. 25, 2024**

Int. Reg. No.: **DM/238982**

Int. Reg. Date: **Jun. 25, 2024**

Int. Reg. Pub. Date: **Aug. 16, 2024**
